SPRAY AERATOR

E Burton Benjamin, Highland Park, Ill., assignor to
Wrightway Engineering Co., Chicago, Ill.

Filed Nov. 25, 1969, Ser. No. 20,272

Term of patent 14 years

Int. Cl. D23—01

U.S. Cl. D23—35

FIG. 1 is a perspective view of a spray aerator embodying my new design;

FIG. 2 is a front elevational view thereof;

FIG. 3 is a side elevational view thereof;

FIG. 4 is a top plan view thereof; and

FIG. 5 is a bottom plan view thereof.

I claim:

The ornamental design for a spray aerator, substantially as shown.
